UNITED STATES PATENT OFFICE

127,580

DESIGN FOR A MOTOR UNIT FOR OPERATING MOTION DISPLAYS

Milton S. Dunkelberger, Dayton, Ohio

Application July 18, 1940, Serial No. 93,767

Term of patent 14 years

To all whom it may concern:

Be it known that I, Milton S. Dunkelberger, a citizen of the United States, residing in the city of Dayton, in the county of Montgomery and State of Ohio, have invented a new, original, and ornamental Design for a Motor Unit for Operating Motion Displays, of which the following is a specification, reference being had to the accompanying drawing, forming a part thereof.

Figure 1 is a perspective view of a motor for operating motion displays showing my new design.

Figure 2 is an end elevational view of the same.

Figure 3 is a side elevational view of the same.

The opposite side of the device from that shown in Figures 1 and 3 of the drawing is substantially similar to that shown in said figures.

I claim:

The ornamental design for a motor unit for operating motion displays, substantially as shown and described.

MILTON S. DUNKELBERGER.
